TOY TYPEWRITER

Samuel I. Berger, Newark, N. J.

Application November 19, 1947, Serial No. 786,903

6 Claims. (Cl. 197—47)

1

It is among the objects of my present invention to provide a toy typewriter which has all the advantages of that of my prior applications Serial No. 658,318, filed March 29, 1946, and since issued as Patent No. 2,486,702, dated November 1, 1949, Serial No. 724,043, filed January 24, 1947, and since issued as Patent No. 2,458,137, dated January 4, 1949, and Serial No. 731,318, filed February 27, 1947, and my previous issued Patent No. 2,398,765, dated April 23, 1946, including the use substantially solely of sheet metal and rod stock to simulate the appearance of a genuine portable typewriter by a greatly simplified construction and which has the further advantage over said prior inventions of enhanced reliability in inking.

In the accompanying drawings in which is shown one of various possible embodiments of the several features of the invention,

Fig. 1 is a plan view of a toy typewriter according to the present invention, showing its general appearance with the simulated keyboard and associated structure in place thereon,

Fig. 2 is a transverse sectional view thereof taken along line 2—2 of Fig. 1,

Fig. 3 is a view similar to Fig. 2, with the key lever depressed, showing the type wheel in typing position,

Fig. 4 is a sectional detail view of the type head and inking mechanism taken along line 4—4 of Fig. 2, and

Fig. 5 is a perspective view of the ink roller mount.

Since the construction in its general outline follows closely that of the applications and patent above identified, being substantially similar to the construction shown in application Serial No. 731,318, only so much of the construction has been shown as is needed to afford a clear understanding of the present improvements, and the general description will be correspondingly brief.

Referring now to the drawings, as shown in Fig. 1, the toy typewriter simulates the appearance of a modern portable typewriter presenting as it does a base 11 supported obliquely as shown, by legs 17, and having a simulated standard keyboard 12 thereon. This keyboard may be directly printed on the rectangular platform 13 or printed on a rectangular sheet metal plate which is affixed to the surface of the platform. A standard at the center of the base supports the operating mechanism of the device and a platen structure 14 is mounted on the base to the rear of the standard. Inasmuch as the platen structure 14 is substantially identical with

that of my prior application Serial No. 731,318, it will not be further described.

A key lever 19 is pivoted on an axle 20, the latter being journalled in side walls 21 rising from the lateral edges of a rectangular bracket 22 affixed to the platform 13. Each of the arms 24 of the key lever 19 is pivoted to a link 25, the upper end of said link being pivoted by means of an axle 26 to the obliquely extending arms 30 of a substantially U-shaped sheet metal carriage 31 which supports a U-shaped bracket 33 depending therefrom. The end of each of said oblique arms 30 is pivoted as at 32 to upstanding ears 27 rising from the rear end of each side of the bracket 22.

A type wheel 35 having on its periphery the type heads comprising the sequence of letters and numerals, is provided, affixed to a substantially upright axle 36 journalled in bearing openings 37 and 38 in bracket 33 and carriage 31, respectively, and protruding therefrom, the axle in position of rest being at substantially right angles to platform 13.

The type wheel 35 is adjustable to a selected setting by means of a rotatable cup shaped knob 45, preferably integral with rotatable dial 39 which bears the sequence of letters and numerals on its upper surface, and which is affixed to the protruding end of axle 36 by set screw 41. A pointer 47 struck out from carriage 31 and positioned so as to be near the periphery of said dial 39 indicates the selected setting thereof. A coil spring 43 surrounding said axle 36 between the type wheel and the carriage serves to take up any looseness and retain the axle in position between carriage 31 and bracket 33.

Ratchet means which includes a horizontal ratchet wheel 48 interposed between bracket 33 and type wheel 35 and affixed to axle 36 by a set screw 49 is preferably provided to step the type wheel around in effecting setting thereof by the turning of knob 45. As this mechanism has been fully described in my above identified applications and patent, it will not be more fully described herein.

The construction thus far described is not necessarily claimed herein as it is the subject of my prior patent and applications above identified.

According to the present invention, a substantially U-shaped bracket 50 is provided for applying ink to the type heads. The arms 51 and 52 of bracket 50 are pivotally mounted on substantially upright axle 36 so as to straddle the type wheel 35 with arm 52 extending beneath bracket 33 and arm 51 resting against the top of type

wheel 35 and being held thereagainst by coil spring 43 so that the bracket acts as a crank in the manner hereinafter set forth.

The vertical cross piece 53 of crank 50, which extends beyond the periphery of the type wheel, has a pair of tongues 54 struck out therefrom and at right angles thereto forming a slot 56 in the cross piece. The tongues carry a vertical rod 57 on which is rotatably mounted a sleeve 58 to which an ink retaining absorbent roller 59, which is itself conventional, is affixed. The roller is of such diameter that a portion of its periphery will extend through slot 56 and abut against the type heads on the periphery of the type wheel.

Arm 52 of the crank has an ear 61 rigid therewith and extending laterally therefrom at one edge thereof. Pivotaly connected to ear 61 as at 62 is one end of a link 63. The other end of the link 63 is pivotally connected as at 64 to the upper end of an upstanding arm 65, the lower end of which is affixed to platform 13.

In the normal or idle position of the machine, the ink roller 59 is in engagement with the type wheel as best shown in Figs. 2 and 4. When the type wheel 35 is rotated by knob 45 to select the desired letter to be printed, the ink roller will also rotate to cover with ink the type heads rolled thereover.

To imprint the selected letter on the paper, key lever 19 is depressed, thereby pivoting carriage 31 about its pivots 32 from idle position shown in Fig. 2 to operating position shown in Fig. 3.

During the course of the movement of carriage 31 with axle 36 and crank 50 thereon, toward the platen, link 63, which does not move forward inasmuch as it is pivotally connected at one end to arm 65 rigid with the platform, will thereupon pull on ear 61 of arm 52 to which it is connected, thereby causing crank 50 to rotate about axle 36 in a counterclockwise direction from the position shown in solid lines in Fig. 4 to the position shown in dot and dash lines in Fig. 4.

As the crank 50 rotates on axle 36, roller 59 will ride over a portion of the periphery of type wheel 35, thereby inking the type heads thereon. In the fully depressed position of key lever 19, when the selected type has contacted the paper, crank 50 will have been rotated by link 63 so that roller 59 thereon will completely have cleared the platen structure 14, as best shown in Fig. 4. Thus there is no danger of the roller contacting the paper during the printing operation to cause smudging and blotting of the paper.

Upon release of the key lever 19, the weight of the carriage 31 will cause the latter to pivot to its idle position. During the course of such movement, link 63 will push on ear 62, thereby rotating crank 50 in a clockwise direction on axle 36 so that roller 59 will return to its original position ready for the next letter to be imprinted.

To enclose the operating mechanism supported by side walls 21 of bracket 22, a substantially U-shaped cover piece 87 is provided which is affixed to the base of the bracket 22. Key lever 19 has a panel 89 unitary therewith and extending upwardly therefrom, as shown in Figs. 2 and 3. When key lever 19 is at rest position, panel 89 will enclose the type wheel and its associated mechanism. Panel 89 has an inwardly turned lip 90 to which are affixed rubber bumpers 91 which abut against a downwardly turned skirt 92 on the front of carriage 31 when the latter has pivoted to rest position under the influence of gravity after key lever 19 has been released.

Bumpers 91 and skirt 92 serve as a stop to properly position the carriage in rest position and prevent bracket 33, which depends from carriage 31, from hitting cover 87 which is of relatively thin sheet metal, and possibly denting said cover and jamming the mechanism thereunder.

Thus by the construction herein described, a relatively inexpensive toy typewriter is provided which is simple to operate and which functions without danger of jamming of the mechanism thereof and without smudging of the imprinted letters or numerals.

As many changes could be made in the above construction and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. In a typewriting mechanism, the combination of a base, a platen structure mounted on said base at the rear thereof, a carriage pivoted on said base, a type wheel having a substantially upright axle bearing in said carriage, means pivotally mounted on said axle to ink said type wheel, said means comprising a substantially U-shaped crank, the arms of which straddle said type wheel, and an absorbent roller pivotally mounted on the cross piece of said crank and in engagement with the periphery of said type wheel, a dial affixed to the upper end of said axle to rotate the latter and said type wheel thereon, and a pointer rigid with said carriage and coacting with said dial to indicate the setting thereof.

2. The combination set forth in claim 1, in which means are provided to pivot said crank on said axle, thereby moving said roller across a portion of the periphery of said type wheel to ink the type heads thereon.

3. In a typewriter mechanism of the type comprising a base, a platen structure mounted on said base at the rear thereof, a carriage pivoted on said base, means to pivot said carriage, a substantially upright axle bearing in said carriage, a type wheel affixed on said axle and coacting with said platen as said carriage is pivoted, a dial affixed to the upper end of said axle to rotate the latter and the type wheel thereon, ratchet means coacting with said type wheel for retaining the latter in set position, and a pointer rigid with said carriage to indicate the setting of said type wheel; the combination therewith of means pivotally mounted on said axle to ink said type wheel as said carriage is pivoted and before said type wheel coacts with said platen, said means comprising a substantially U-shaped crank having a pair of arms pivotally mounted on said substantially upright axle, an ink absorbent roller mounted on the cross piece of said crank and in engagement with said type wheel, an ear extending laterally from the lower arm of said crank and a link pivotally connected to said ear and to the base of said typewriter whereby, when said carriage is pivoted, said crank will be pivoted about said axle by the action of said link to move said roller horizontally across said type wheel.

4. In a typewriter mechanism of the type comprising a base, a platen structure mounted on said base at the rear thereof, a bracket affixed to said base, a carriage pivoted on said

bracket, a substantially upright axle bearing in said carriage and having affixed thereon in co-axial relation therewith, a ratchet wheel and a type wheel, said ratchet wheel retaining said type wheel in set position, means for rocking said carriage on said bracket from rest to typing position to move said type wheel into contact with said platen, said means comprising a key lever pivoted to said bracket and having a panel unitary therewith and extending upwardly therefrom to conceal said type wheel and said ratchet wheel when said carriage is in rest position, and a link connecting said key lever to said carriage for pivoting the latter, said panel having an inwardly turned lip at the upper edge thereof which abuts against said carriage to limit the movement thereof as it pivots to rest position; the combination therewith of a substantially U-shaped crank having a pair of arms pivotally mounted on said substantially upright axle and straddling said type wheel, a pair of opposed tongues struck out from the cross piece of said crank and forming a slot therein in juxtaposition to the periphery of said type wheel, an ink absorbent roller rotatably mounted between said tongues, extending through said slot and in engagement with said type wheel, an ear extending laterally from the lower arm of said U-shaped crank, and a link pivotally connected to said ear and to the base of said typewriter, whereby when said carriage is pivoted, said crank will be pivoted about said axle by the action of said link to move said roller horizontally about said type wheel.

5. In a typewriting mechanism, the combination of a base, a platen mounted on said base, a bracket affixed to said base, a substantially U-

shaped carriage pivoted on said bracket and having a downwardly turned skirt on the front edge thereof, a type wheel rotatably mounted on said carriage, means for rocking said carriage on said bracket from rest to typing position to bring said type wheel in contact with said platen, said means comprising a key lever pivoted to said bracket and having a panel unitary therewith and extending upwardly therefrom, and a link connecting said key lever to said carriage for tilting the latter, said panel having an inwardly turned lip at the upper edge thereof, and a plurality of bumpers affixed to said lip, said bumpers abutting against the downwardly turned skirt on said carriage to limit the movement of the latter as it pivots to rest position.

6. As an article of manufacture, a substantially U-shaped crank having a pair of arms, a pair of opposed tongues struck out from the cross piece of said crank and forming a slot therein, an ink absorbent roller rotatably mounted between said tongues and extending through the slot in said cross piece, and an ear extending laterally from the lower arm of said U-shaped crank.

SAMUEL I. BERGER.
